UNITED STATES PATENT OFFICE

2,223,003

CHIMNEY COWL

Daniel Friedman, Chicago, Ill.

Application March 3, 1939, Serial No. 259,685

1 Claim. (Cl. 98—68)

The present invention relates to an improved chimney cowl of the streamlined type expressly designed to promote efficient draft and to minimize down draft.

By way of introduction, it is to be pointed out that the structure herein depicted and claimed is generic to that disclosed in my co-pending application Serial No. 259,686 filed in the United States Patent Office, March 3, 1939, thus making it advisable to consider the two applications conjointly to obtain a comprehensive understanding of these distinguishable contributions to the art.

Generically stated, one phase of the invention deals with the aforementioned streamlined hood, this having an upstanding and crowning wind vane and being provided on its interior with a predetermined form of attaching and retention bracket of a type capable of use interchangeably with varying chimney pipe fixtures standardized by me for selective accommodation of said bracket.

Specifically, novelty is predicated on a sturdy annular attaching band connectible with the chimney pipe and provided with a single properly shaped and stabilized spindle member for co-operation with said hood bracket.

In reducing to practice the principles of the invention I have devised a structural assembly possessed of simplicity and economy and one, which it is believed, may be justly and unreservedly endorsed by the trade as aptly fitted for the purposes intended.

Other features and advantages will become more readily apparent from the following description and the accompanying illustrative drawing.

In the accompanying drawing showing the preferred embodiment of the invention and wherein like reference characters are utilized to designate corresponding parts:

Figure 1 is a fragmentary sectional view of a part of the chimney pipe showing the improved cowl assembly, as constructed in accordance with this invention, operatively associated therewith.

Figure 2 is a front view, that is, a view observing Figure 1 in a direction from right to left, the parts being in elevation and the clamping or attaching band being in section.

Figure 3 is a top plan view of Figure 2.

Figure 4 is a top plan view of the special adapter ring or band and spindle arrangement.

In the drawing the chimney pipe, this being conventional, is denoted by the numeral 5. In accordance with the present invention I provide an adapter ring or band 6 and this is of a pre-

determined diameter to externally surround the upper end of the pipe 5. The ring is fastened flush in place by suitable bolts or equivalent fasteners 7. The supporting unit comprises a centrally positioned perpendicular spindle 8, this forming the upper end of a rod 9. The intermediate portion of the rod 9 is bent laterally and downward and the lower end is welded or otherwise secured to the supporting and adapter ring as at 10. It will be noticed that the inclined intermediate portion of the rod is housed in a reinforcing sheet metal sheath 11. The sheath surrounds the rod and the lower end is formed into an extension 12, this being welded or otherwise secured to said ring 6 as shown to advantage in Figures 1 and 4.

The streamlined hood or cowl per se is denoted by the numeral 13. It has a substantially triangular crown portion and this is formed of companion sectors 14 and 15 having their adjacent edges overlapping as at 16 and suitably fastened together as at 17. The section 14 is provided with an extension which is bent up at right angles to form an appropriately designed wind vane 18. The body portion comprises diverging walls 19 and an inclined bight or connective wall 20. These walls are shaped to provide the desired streamlined effect. For sake of rigidity a bead is fashioned as at 21 and below this is the substantially U-shaped skirt 22.

The attaching and retention bracket 23 is on the interior. This comprises a strap of metal 24 riveted in place as at 25 and having its free end bent into a double-U formation. This provides upper and lower guide bearings 26 and 27 and an end thrust or abutment member 28 to accommodate the extreme upper end of the so-called spindle 8. The spindle 8 has a retaining pin, cotter key or the like 29 engageable with the limb 27, this being slipped in place after the parts are assembled to maintain the same properly assembled. The numeral 30 designates a cross-piece or reinforcing brace carried by the hood and connected with the twin-U guide and thrust means. Thus, the hood can be detachably and rotatably mounted on the spindle, in an obvious manner.

It is thought that the description taken in connection with the drawing will enable a clear understanding of the invention to be had. Therefore, a more lengthy description is thought unnecessary.

While the preferred embodiment of the invention has been shown and described, it is to be understood that minor changes coming within the

field of invention claimed may be resorted to if desired.

Having described the invention, what is claimed as new is:

- 5 A chimney cowl comprising a cowl body, a supporting member having its upper end vertically arranged and forming a spindle for rotatably supporting the body, means for connecting the member to the top part of the chimney, a 10 strap having one end portion connected to the under face of the top part of the cowl body with the major portion of the strap bent into substantially 8-shape to provide a horizontal arranged

top part and a pair of spaced horizontal parts each having a hole therein for the passage of the spindle with the upper end of the spindle bearing against the first-mentioned horizontal part, a pin passing through the spindle part between the 5 pair of horizontal parts, a brace strap connected at its ends to side parts of the body with an intermediate portion connected to the 8-shaped portion adjacent the lower end thereof and a brace plate extending from the upper edge of said 10 brace member to that part of the strap which is connected with the top of the cowl body.

DANIEL FRIEDMAN.
